UNITED STATES PATENT OFFICE.

JOHN HENRY NELSON, OF NEW CASTLE, PENNSYLVANIA.

CLOTHES-HANGER CABINET.

1,345,624.

Specification of Letters Patent.

Patented July 6, 1920.

Application filed August 4, 1919. Serial No. 315,254.

To all whom it may concern:

Be it known that I, JOHN HENRY NELSON, a citizen of the United States, residing at New Castle, in the county of Lawrence and State of Pennsylvania, have invented certain new and useful Improvements in Clothes-Hanger Cabinets; and I do declare the following to be a full, clear, and exact description of the invention, such as will 5 enable others skilled in the art to which it appertains to make and use the same.

This invention relates to clothes-hangers, also to cabinets, and it relates more specifically to what might be termed a clothes-hanger cabinet.

One object of this invention is to generally improve upon devices of this character by providing an improved foldable clothes-hanger that is exceedingly strong, durable, 20 rigid and compact, consistent with lightness and low cost of manufacture, and in which the supporting levers are thoroughly protected from dust and are very efficiently supported by a series of superposed shelves 25 which alternate with one or more superposed series of supporting bars.

Other objects and advantages may become apparent to persons who read the following details of description in connection with the 30 accompanying drawings in which:—

Figure 1 is a front view of a device constructed in accordance with the present invention, the door being omitted.

Fig. 2 is a horizontal sectional view, the 35 section being taken between two of the shelves.

Fig. 3 is a transverse vertical sectional view, the section being taken along the line 3—3 of Figs. 1 and 2.

Fig. 4 is a view similar to Fig. 2, but 40 illustrating a somewhat modified form of the invention.

Fig. 5 is a view similar to Fig. 3, but illustrating the modified form shown in Fig. 45 4, the section being taken along the line 5—5 of Fig. 4.

Fig. 6 is a view similar to Fig. 4, but portions of the supporting bars being broken off, and the same being shown in the extended or clothes-supporting position.

Referring to these drawings in detail, in which similar reference characters correspond with similar parts throughout the several views, the device illustrated in Figs. 1, 2 55 and 3 comprises a series of superposed shelves or plates 1, 2 and 3, the shelf 1 con-

stituting the top or cover plate of a box or casing and the shelf 2 constituting the bottom or floor plate of the box or casing. The shelves 3 constitute partition-plates. 60 End walls 4 are united with the shelves or plates 1 and 2 so as to secure them in fixed position to one another, a rear wall 5 closes the rear side of the casing, and a door 6 closes the front of the casing. Corner 65 brackets 7 extend around the corners of the cabinet and are secured thereto by any appropriate means so as to add strength and rigidity to the structure. The end walls 4 are preferably formed with horizontal 70 grooves 8 which are spaced equi-distant from one another, and the ends of the shelves 3 are fitted in these grooves so that the spaces between the shelves are equal in vertical extent. The door 6 is preferably hinged at 75 9 and adapted to swing downward and depend from the lower shelf 2 when the box is open for use, and any appropriate form of lock or latch 10 may be provided on the upper shelf 1 for engaging with the door 6 80 and holding it closed.

Two series of supporting bars 11 are arranged in alternate relation with the shelves 1, 2 and 3; that is, each bar of each series has one end seated between two adjacent 85 shelves and has its upper and lower surfaces touching the respective lower and upper surfaces of contiguous shelves, and a pivot-rod 12 extends through the relatively thick ends of the bars 11 and through the 90 entire series of shelves so as to pivotally connect these bars to the shelves in such relation that the shelf above each bar coacts with the shelf below and with the pivot-rod 95 for supporting the respective bars against sagging or being depressed from the horizontal position. For this purpose, the pivot bearing of each bar 11, through which the pivot-rod 12 extends, is located at a distance from the end of the bar sufficient to provide 100 a short arm 11' which bears upward against the superjacent shelf while the long arm 11^a bears down on the subjacent shelf. Moreover, it will be seen that the pivot-rod 12 is supported against bending in consequence 105 of its engagement with each of the shelves, which increases the efficiency of each rod 12 as a support for the bars 11. These bars are preferably of the same vertical extent or height throughout their length, but are tapered from their inner ends to their outer ends with regard to their horizontal extent 110

or width, and this not only results in the saving of material in manufacturing the device, but also provides for overlapping these bars upon one another in the relation shown in Figs. 2 to 5 inclusive.

Each pivot-rod 12 is preferably provided with a supporting loop 13, and these loops 13 are attachable to hooks, or other supporting means (not shown) for suspending the 10 box against a wall of a room in which the device is to be used. Collars or enlargements 14 are fixed to the rods 12, and nuts 15 coat with the elements 12 and 14 for additionally securing the shelves in fixed position relative to one another.

Referring to the modified form shown in Figs. 4, 5 and 6, it will be seen that the end walls 4' are longer from front to rear than the previously mentioned end walls 4, also, 20 that the shelves or plates 1', 2' and 3' are wider than the previously mentioned shelves 1, 2 and 3. In addition to the supporting bars 11 and pivot-rods 12 of this modified structure, two series of supporting arms 16 25 and their corresponding pivot-rods 17 are provided. These pivot-rods 17 may be constructed as previously described for the pivot-rods 12, and no further description thereof seems necessary. However, the 30 pivot-rods 17 are located adjacent to the rear edges of the shelves, whereas the pivot-rods 12 are located adjacent to the front edges thereof, or in other words, the rear pivots are located between the longitudinal 35 center and rear edge, whereas the pivot-rods 12 are located between the longitudinal center and the front edge. Moreover, the pivot-rods 17 are located farther inward

from the ends 4' than the pivot-rods 12, so that when the supporting bars 11 are swung 40 forward into their useful position the supporting bars 16 may also be swung forward into their useful position without interference with or by the bars 11, but are spaced a sufficient distance from the bars 11 to 45 provide a considerable air-space between garments which hang on the supporting rods 11 and 16.

Although I have described these embodiments of my invention very specifically, it is 50 not intended to limit this invention to these exact details of construction, but changes may be made within the scope of the inventive ideas as implied and claimed.

What I claim as my invention is:— 55

In a foldable clothes-hanger, the combination of a box including end walls, a cover-plate, a floor-plate, partition-plates extending from one to the other of the end walls and engaged therewith in a manner to secure them against relative vertical movement, series of supporting bars arranged in alternate relation with said plates and having their upper and lower surfaces slidably fitted against the lower and upper surfaces of said plates, and rods extending through said plates and bars and coacting with said end walls to secure the plates in fixed relation to one another and to pivotally secure said bars to said plates, each of 60 said rods being formed with a loop at its 65 upper end for receiving a suspending element.

In testimony whereof I have hereunto set my hand.

JOHN HENRY NELSON.
